RAILWAY TRAFFIC CONTROLLING
APPARATUS

Charles H. Lay, Swissvale, Pa., assignor to The
Union Switch & Signal Company, Swissvale,
Pa., a corporation of Pennsylvania

Application January 19, 1940, Serial No. 314,652

14 Claims. (Cl. 246—134)

My invention relates to railway traffic controlling apparatus, and more particularly to improvements in interlocking control systems of the type in which the track switches and signals of a track layout are governed, as required to establish different traffic routes, by the operation of push buttons or the like identified with the opposite ends of the routes.

One object of my invention resides in an improved arrangement of route selecting circuits for a system of this character, in which a relatively small number of relays and contacts are used, and in which each button normally serves to designate the entrance end of a route and becomes conditioned to identify the exit end of a route only in response to the operation of the button identifying the opposite end of such route.

Another object of my invention resides in the provision of means whereby but one route can be set up at a time. The apparatus of my invention functions in such a manner that the operation of any button to mark the entrance end of a route lights a suitable indicator on the operator's control panel to indicate that a route is being set up and to also indicate the traffic direction for such route, and the subsequent operation of the button for the opposite end of the desired route results in the establishment of the route and the clearing of the signal for the corresponding direction without further action by the operator, and also extinguishes the direction indicator to thereby indicate that any non-conflicting route can be set up.

One feature of my invention resides in the provision of a single directional relay for each direction for conditioning the buttons to mark the exit ends of the routes in place of a separate exit relay for each route exit as heretofore used. Another feature resides in an improved arrangement of route circuits employing a route relay for each switch of a route but avoiding the connection of these relays in series and also avoiding the use of any auxiliary relays other than an entrance relay for each route entrance and the two directional relays mentioned.

Other objects, features and purposes of my invention will be made apparent as the description proceeds.

My invention is an improvement upon those disclosed in the copending application for United States Letters Patent, Serial No. 14,868, for Interlocking control apparatus filed April 5, 1935, by Earl M. Allen and Howard A. Thompson; Serial No. 118,609, for Railway traffic controlling apparatus, filed December 31, 1936, by John M. Pelikan, which corresponds with the French Patent

No. 829,857; and Serial No. 252,803, filed January 25, 1937, for Railway traffic controlling apparatus, by Lloyd V. Lewis.

I shall first describe one form of apparatus embodying my invention and shall then point out the novel features thereof in claims.

Referring to the accompanying drawings, Figs. 1A to 1E, inclusive, taken together illustrate the circuits for a route interlocking system embodying my invention. More particularly, Fig. 1A represents the operator's control panel in which the route buttons, for ready identification, are mounted on a diagram of the track layout to be controlled, at points corresponding to the ends of the routes; Fig. 1B shows the circuits controlled directly by the push buttons when operated to designate the entrance ends of the routes; Fig. 1C shows the route establishing circuits which function when the buttons are operated as exit buttons; Fig. 1D shows a plan of the track layout to be controlled together with the track relays and typical switch control circuits, while Fig. 1E shows the signal control circuits.

Similar reference characters refer to similar parts in each of the separate views.

Referring first to Fig. 1D, in the plan of the track layout chosen to illustrate my invention, for simplicity each pair of track rails constituting a stretch of track is represented as a single line. Although the apparatus of my invention is adapted to control any track layout encountered in practice, the layout shown has been selected as typical, and represents two parallel tracks connected by crossovers comprising the pairs of track switches designated 1A and 1B, 5A and 5B, and 7A and 7B, the lower main track being also connected to a siding by a single switch 3. All of the track switches are in their normal positions, as shown. High speed train movements over the main tracks in the normal direction of running are governed by the main signals 4A and 4B, respectively, while the remaining signals 2, 4B, 6, 8, 10B and 12 are slow speed signals. All of the signals are normally at stop, as shown. It is to be understood that the track rails are divided in the usual manner by insulated joints into sections, the upper track including the detector sections 4T and 5T and the lower track the detector sections 1T and 7T. Each track section is provided with the usual track circuit having a suitable source of current as indicated by the reference character B at one end, and a track relay TR connected across the rails at the other end. Each track relay TR is provided with a slow acting track repeating relay TP, as shown. In the circuit plans shown herein, each relay

or circuit controller is identified by a letter or combination of letters, prefixed by the designation of the switch or signal with which it is associated, the circuits being arranged in the usual written circuit form with similar circuits grouped together in the same views and with each contact identified by a number as well as by the designation of the device which operates it above the contact. Instead of showing the local source of current for energizing the relays, I have shown only the terminals, which are designated in the customary manner by the references B and C.

Each track switch of the layout of Fig. 1D is actuated by a switch machine SM, as illustrated for the crossover switches 1A and 1B, which may be of the type shown in the Zabel Patents Nos. 1,293,290 and 1,413,820, having a reversible motor controlled by a polarized control relay such as relay 1WR, as indicated diagrammatically by dotted line connections in the drawings. It is to be understood that each track switch will be operated to normal, as shown, or to reverse, when the corresponding switch control relay closes its polar contacts to the left or right respectively. Each switch machine SM has a circuit controller as disclosed in the Zabel patents controlling the usual polarized switch indication relay, such as the relay 1WP, each relay WP controlling a pair of repeating relays such as the relays 1NWP and 1RWP, each of which when energized indicates that the associated switch occupies the corresponding normal or reverse position.

The signals may be assumed to be of the well-known searchlight type as disclosed in the Blake Reissue Patent No. 14,940, of August 31, 1920, each having an electromagnetic mechanism controlled by the signal control relay HR of corresponding number shown in Fig. 1E. For an understanding of the present invention, it will suffice to point out that each signal indicates proceed when the associated relay HR is energized and indicates stop when such relay is de-energized. The signals and the track relays control a group of switch locking relays 1LR, 3LR, 5LR and 7LR, shown in Figs. 1C and 1D, for preventing the operation of the track switches except when conditions are proper. For simplicity the circuits for controlling the relays LR have been omitted, suitable circuits being well known. These relays may, for example, be controlled as disclosed in Patent No. 2,179,462, issued November 7, 1939, to H. S. Young, for Railway traffic controlling apparatus.

The control panel of Fig. 1A is provided with a track diagram similar in construction to that shown in the Pelikan application hereinbefore referred to, having a plurality of illuminated strip indicators for indicating the routes that are established and the movements of the trains over such routes and for also indicating the portions of the track switches, and for suitable circuits for controlling these indicators, reference may be made to the Pelikan disclosure. The control panel disclosed herein, however, differs in a number of features from that of Pelikan. The push buttons are of an improved type having centrally located bulls-eyes for displaying the signal indications, these being preferably of the form shown in the pending application of Bone et al., Serial No. 267,684, filed April 13, 1939, for Circuit controllers, while the push buttons employed by Pelikan for individual switch control have been replaced by centrally biased three position levers such as are shown in the Lewis Patent No. 1,887,273. In addition, I have provided a pair of indicators W and

E, one or the other of which is illuminated by lighting the lamp WE or EE, respectively, of Fig. 1B, in response to the operation of a button identifying the entrance end of a route to be established, the lighted lamp becoming extinguished when a second button is operated to designate the desired exit point and thereby complete the establishment of the route.

In the circuit drawings, the push buttons are identified by the reference P with a numerical prefix identifying the location, and function in such a manner that with the apparatus in its normal condition, as shown, the operation of any button completes a pick-up circuit in Fig. 1B for an entrance stick relay PS associated with the button, which relay upon becoming energized will cause a directional stick relay ER or WR to become energized to illuminate the corresponding directional indicator E or W on the track diagram. Thus the buttons for the signals 2, 4, 6, and 8, governing traffic movements from left to right, control relay ER, while the buttons for the signals 10 and 12 governing traffic movements in the opposite direction control relay WR. The circuits for the intermediate signal 8 due to the provision of "through routing" employs two additional relays 8ER and 8WR, as hereinafter explained.

When a directional relay ER or WR becomes energized, the pick-up circuits for all the PS relays are opened, while that relay PS which has been picked up is held energized by the track relay for the entering section of the route which is being set up. It follows that the setting up of another route cannot be initiated until the one already initiated is completed.

The entrance relays PS and the push buttons P are provided not only with the contact equipment shown in Fig. 1B, but with certain additional contacts shown in Fig. 1C by which they jointly control the route relays R for establishing the routes. Each route portion including a track switch has a route relay corresponding to the position of the switch required for such route portion, and having a corresponding designation, as will be readily understood from a comparison of the relays of Fig. 1C with the track plan of Fig. 1D; thus for route 2-3 there is a relay 1ANR for operating the crossover switches 1 to normal, while for route 4-12 there are the route relays 1B-3NR and 5-7BNR, the former for operating crossover 1 and switch 3 to normal, and the latter for operating crossovers 5 and 7 to normal.

When an entrance relay PS becomes energized, it connects terminal C of the source to one end of the circuit for each route relay for each route for which the energized relay PS identifies the entrance end, as shown in Fig. 1C, while the energized directional relay ZR or WR controlled by the energized relay PS connects the other terminal B of the source to contacts of the push buttons P for the exit ends of these routes. The push buttons are thereby conditioned so that the operation of one of these buttons to identify a particular one of the routes referred to completes the circuit for the route relay for the portion of the selected route which is nearest its exit end, whereupon the remaining route relays for the selected route pick up successively in tandem, the last one to pick up releasing the directional relay to restore all the buttons to normal. The route relays for the route thus selected are held energized by the energized entrance relay until a train enters the first section of the route, or until the route is cancelled.

manually by momentarily "pulling" the entrance button.

The energized route relays open back contacts in the circuits for the route relays for all conflicting routes and control the track switches and signals as shown in Figs. 1D and 1E, and also by means not shown control the lights of the track diagram like the relays of corresponding designations in the Pelikan disclosure herein before referred to.

I shall now describe the operation of my apparatus under different assumed conditions by tracing the circuits in detail. I shall first assume that the apparatus is in the normal condition as shown in the drawings, and that the operator desires to clear signal 4A to pass an approaching train over route 4-12. The operator being informed of the approach of the train by the lighting of the usual approach indicator, he will press button 4P momentarily to pick up the entrance relay 4PS. The pick-up circuit for relay 4PS may be traced in Fig. 1B from one terminal B of the source, back contacts 13 and 14 of the directional relays ER and WR, back contact 15 of button 2P and front contact 16 of button 4P, back contacts 17 and 18 of the route relays 1B-3NR and 1RR, relay 4PS, contact 19 of the track relay A'TR for the entering section A'T of route 4-12 to terminal C.

Relay 4PS upon becoming energized completes its stick circuit extending from terminal B at the normally closed "pull" contact 20 of button 4P over the front contact 21 and winding of relay 4PS and contact 19 to terminal C, and also completes a circuit for relay ER from terminal B, back contacts 22 and 23 of relays 1B-3NR and 1RR, front contact 24 of relay 4PS, back contact 25 of relay WR, the winding of relay ER to terminal C.

Relay ER picks up and at contact 26 completes the circuit for lamp EE to light the directional indicator E on the track diagram, and at back contact 13 disconnects terminal B from the pick-up circuits for the relays PS, and connects terminal B at back contact 27 of relay WR, Fig. 1C, over its front contact 28 to contacts 29 and 30 of buttons 8P and 10P and to contacts 31 and 32 of button 12P, which buttons correspond to the exit ends of routes for which relay 4PS identifies the entrance end. Relay 4PS, by closing contact 33 connects terminal C to the circuit for the route relay 1RR for route 4-8, and by closing contacts 34, 35 and 36 connects terminal C to the circuits for relays 1B-3NR, 5RR and 7ANR for route 4-10 via reversed, contact 35 also connecting terminal C to the circuit for relay 5-7BNR which with relay 1B-3NR governs route 4-12.

Buttons 8P, 10P and 12P are now conditioned to function as exit buttons, and buttons 2P, 4P and 6P are temporarily non-operative. If button 12P is now operated to complete the set-up for route 4-12, a circuit is closed from terminal B at back contact 27 of relay WR, front contact 28 of relay ER, contacts 29, 30 and 32 of buttons 8P, 10P and 12P, back contacts 37 and 38 of relays 12PS and 7RR, the winding of relay 5-7BNR, front contacts 39 and 40 of relays 1LR and 1NWP, in multiple, back contact 41 of relay 5RR, front contacts 42 and 43 of relays 5LR and 5NWP, in multiple, back contacts 44 and 45 of relays 6PS and 3RR, front contact 35 of relay 4PS, back contact 46 of relay 1RR to terminal C. Relay 5-7BNR therefore picks up, and at contact 47 completes a stick circuit so that it remains energized after button 12P is released, and also com-

pletes a circuit for relay 1B-3NR from terminal B at front contact 48 of relay 5-7BNR over back contacts 49 and 50 of relays 12PS and 7RR, front contacts 51 and 52 of relays 3LR and 3NWP in multiple, back contact 53 of relay 3RR, front contacts 54 and 55 of relays 1LR and 1NWP in multiple, the winding of relay 1B-3NR, back contact 56 of relay 1RR, front contact 34 of relay 4PS to terminal C.

Relay 1B-3NR therefore becomes energized 10 and by opening its back contact 22, Fig. 1B, de-energizes relay ER, thereby extinguishing indicator E and restoring the circuits controlled by the buttons P to normal, with certain exceptions. Thus the circuit for the conflicting entrance relay 15 6PS, Fig. 1B, is held open at back contact 57 of relay 1B-3NR, and the circuit for the opposing entrance relay 12PS is held open at back contact 58 of relay 5-7BNR. Furthermore, only those routes which do not conflict with route 20 4-12, such as routes 2-8 and 3-10 or the opposing route 10-2, can now be set up, for the reason that the circuits for the route relays 1RR and 3RR in Fig. 1C are open at back contacts 59 and 60 of relay 1B-3NR, and the circuits for 25 relays 5RR and 7RR are open at back contacts 61 and 62 of relay 5-7BNR, and only the route relays 1ANR, 5ANR and 7ANR remain operative.

Referring now to Fig. 1D, it will be seen that relay 1B-3NR when energized completes the normal energizing circuit for the polarized switch control relay 1WR from terminal B, contact 63 of relay 1LR, the left-hand or normal winding of relay 1WR, contacts 64 and 65 of relays 1LR and 1B-3NR to terminal C, to operate the crossover 30 switches 1A and 1B to normal, as required, and it is to be understood that relay 1B-3NR also controls a similar relay WR to operate switch 3 to normal and that relay 5-7BNR likewise controls two relays WR to operate the crossover 35 switches 5A, 5B, 7A and 7B to normal as required. When the track switches assume the normal position all of the polarized indication relays WP become energized in the normal direction and each of the indication repeating relays 1NWP, 3NWP, 45 5NWP and 7NWP is energized, and a signal circuit is completed in Fig. 1E from terminal B, back contact 66 of relay 12PS, front contacts 67, 68 and 69 of relays 5NWP, 5-7BNR and 7NWP, front contacts 70, 71 and 72 of relays 3NWP, 50 1NWP and 1B-3NR, front contacts 73, 74 and 75 of relays 4PS, 1NWP and 5NWP, relay 4AHR to terminal C, to energize the signal control relay 4AHR to thereby clear the signal 4A governing traffic movements over the established route 55 4-12.

Assuming now that the approaching train passes signal 4A and enters the first section A'T of the route, the track relay A'TR and its repeater A'TP will release successively, relay A'TR 60 by opening its front contact 19 releasing relay 4PS, which relay by opening contacts 34, 35 and 73 will release relays 1B-3NR, 5-7BNR and 4AHR, thereby cancelling the route set-up. It is to be understood that the switch locking relays 65 1LR, 3LR, 5LR and 7LR become deenergized in the usual manner to lock the switches of the established route when signal 4A is cleared, and that relay 1LR remains deenergized until section A'T or 1T is vacated, relay 3LR until section 3T 70 is vacated, relay 5LR until section 3T or 5T is vacated, and relay 7LR until section 5T or 7T is vacated. It will be seen therefore that these relays prevent the establishment of any conflicting route as long as any of the sections are oc- 75

cupied. As long as section A1T is occupied the circuit for the conflicting route relay 1RR in Fig. 1C is held open at contact 76 of relay 1LR; as long as section 3T is occupied, the circuits for the relays 3RR and 5RR are held open at contacts 77 and 78 of relays 3LR and 5LR, while the circuit for relay 7RR is held open at contact 79 of relay 7LR until section 7T is vacated.

My apparatus is also arranged to permit a train to enter a route already occupied by a preceding train. This is accomplished in the usual manner by providing a back contact of the track repeating relay TP for bridging the contact of the track relay TR in the circuit for each relay PS.

I shall next assume that with the apparatus in the normal condition as shown that buttons 4P and 12P are operated in the reverse order to set up route 12-4 for a train movement from right to left. The momentary operation of button 12P completes a circuit in Fig. 1B from terminal B over back contacts 13 and 14 of relays ER, WR, back contacts 15, 16 and 80 of buttons 2P, 4P and 6P, front contact 81 of button 12P, back contacts 58 and 82 of relays 5-7BNR and 7RR, winding of relay 12PS, contact 83 of the track relay 7TR to terminal C. Relay 12PS therefore picks up and establishes its stick circuit at contact 84, and at front contact 85, Fig. 1C, connects terminal C to the circuits for relays 1ANR and 1RR. At front contacts 49, 66, 87 and 37, relay 12PS connects terminal C to the circuits for relays 3RR, 1B-3NR, 5ANR, 7RR and 5-7BNR, while at contact 90, Fig. 1B, it completes a circuit over back contacts 88, 89 and 91 of relays 5-7BNR, 7RR and ER for relay WR.

Relay WR picks up and at contact 92 completes the circuit for lamp WE to light the directional indicator W on the track diagram, and at back contact 14 disconnects terminal B from the pick-up circuits for the relays PS, and connects terminal B at its front contact 27, Fig. 1C, to the contacts of the buttons 2P, 4P and 6P to thereby condition these buttons as exit buttons.

If button 4P is now operated to complete the set-up for route 12-4, a circuit is closed from terminal B at front contact 27 of relay WR, Fig. 1C, normally closed contact 93 of button 2P, normally open contact 94 of button 4P, the center contact 157 of the individual switch lever 1P, contact 95 of relay 12PS, and thence over back contact 34 of relay 4PS through relay 1B-3NR to terminal C at front contact 49 of relay 12PS.

Relay 1B-3NR picks up, completing its stick circuit at contact 96 and at contact 97 connects terminal B to the circuit through relay 5-7BNR to terminal C at front contact 37 of relay 12PS. Relay 5-7BNR opens back contact 88, Fig. 1B, to release relay WR, and relay 1B-3NR opens its back contacts 17 and 57, Fig. 1B, in the circuits for the opposing relays 4PS and 6PS. The route relays for route 12-4 are now energized to operate the switches to normal as already described for route 4-12, but the signal circuit in the case of route 12-4 extends from terminal B at back contact 73 of relay 4PS, Fig. 1E, over front contact 66 of relay 12PS through relay 12HR to terminal C, so that signal 12 is cleared in place of signal 4A.

I shall next assume that with the apparatus in the normal condition that buttons 4P and 8P are operated to set up route 4-8. In this case relay 4PS is energized in response to the operation of button 4P as hereinbefore described, and the subsequent operation of button 8P completes a circuit in Fig. 1C over front contact 29 of button

8P and contact 98 of relay 4PS, through relay 1RR to terminal C at front contact 33 of relay 4PS. Relay 1RR picks up and opens its back contacts 99 and 56 in the circuits for the conflicting route relays 1ANR and 1B-3NR. By opening its back contact 23, Fig. 1B, relay 1RR releases relay ER. Relay 1RR also opens contact 100 in the circuit for relay 2PS. Relay 1RR is held energized by relay 4PS after button 8P is released by the stick circuit shown in Fig. 1C and including its own front contact 101. By closing contact 102, Fig. 1D, relay 1RR operates relay 1WR to reverse, thereby causing the switches 1A and 1B and relay 1WP to be reversed whereupon relay 1NWP releases and 1RWP picks up. Relay 1RWP then completes the signal circuit in Fig. 1E from terminal B, front contacts 103 and 104 of relays 4PS and 1RWP, back contact 105 of relay 2PS, front contacts 106, 107 and 73 of relays 1RWP, 1RR and 4PS back contact 74 of relay 1NWP, relay 4BHR to terminal C. Relay 4BHR therefore becomes energized to clear signal 4B for route 4-8.

I shall next assume that with the apparatus in the normal condition buttons 2P and 8P are operated to set up route 2-8. The operation of button 2P by closing contact 15, Fig. 1B, effects the energization of relay 2PS, and relay 2PS upon becoming energized closes contact 108 to pick up relay ER, and also closes contact 109 to pick up relay 8ES, provided relay 5RR is not energized, for a purpose to be described herein-after, the operation of relay 8ES being idle in the present instance. The subsequent operation of button 8P completes a circuit over its front contact 29, Fig. 1C, and contacts 110 and 111 of relay 2PS to pick up relay 1ANR, and relay 1ANR upon becoming energized closes contact 112, Fig. 1D, to operate relay 1WR to normal to restore the switches 1A and 1B to normal, as shown. Relay 1ANR also closes contact 113, Fig. 1C, to complete its stick circuit, and opens back contacts 114 and 115 in the circuits for relays ER and 8ES in Fig. 1B. Relay 8ES releases, but relay ER is held energized until the operator releases button 8P by a stick circuit including contact 116 of relay ER and contact 117 of button 8P. Relay 1ANR when energized prevents the energization of the conflicting route relay 1RR by opening its back contact 118, Fig. 1C. The signal relay 2HR, Fig. 1E, becomes energized when the switches assume the normal position to energize relay 1NWP over the circuit from terminal B at front contact 105 of relay 2PS, contacts 119, 120 and 121 of relays 1NWP, 1ANR and 2PS, relay 2HR to terminal C, thereby effecting the clearing of signal 2 for route 2-8.

I shall next assume that after route 4-8 or 2-8 has been set up, that buttons 8P and 10P are operated to set up route 8-10. Button 8P becomes conditioned as an entrance button by the release of relay ER due to the opening of contact 117, Fig. 1B, so that the second operation of button 8P completes the pick-up circuit for relay 8PS from terminal B at contact 13 over contact 122 of button 8P, and relay 8PS picks up to complete the pick-up circuit for relay 8ES at contact 123, and that for relay ER at front contact 124. Relay 8ES picks up and by closing contacts 125, 126 and 127, Fig. 1C, connects terminal C to the circuits for the route relays 7ANR, 7RR and 5ANR for routes 8-10 and 8-12. If button 10P is now operated, the closing of its front contact 30 completes a circuit for relay 1ANR extending to terminal C at front contact 125 of relay 8ES, and relay 1ANR picks up to

establish its stick circuit at contact 128 and to complete the circuit for relay 5ANR extending from terminal B at contact 129 of relay 7ANR through relay 5ANR to terminal C at front contact 127 of relay 8ES. Relay 5ANR therefore picks up and by opening its back contact 130, Fig. 1B, releases relay ER. Relay 8PS is now held energized over the stick circuit extending from terminal B, the normally closed "pull" contact 131 of button 8P, front contact 132 of relay 8PS, back contact 133 of relay 1RR, relay 8PS, front contact 134 of the track relay 5TR for the entering section 5T of route 8-10, to terminal C. Relay 8ES is held energized over contacts 123 and 134 of relays 8PS and 5TR, and at its front contact 135, Fig. 1E, completes the circuit for the signal relay 8HR for clearing signal 8 to permit a train movement over route 8-10, in a manner similar to that already described for other routes.

The operations required to set up route 8-12 and for clearing signal 8 for a train movement over that route are so similar to the operations already described that a detailed description is believed unnecessary.

It will also be clear from the foregoing that the operator may set up the through route 2-10 or 2-12 by first setting up route 2-8 and then setting up route 8-10 or 8-12. There are, however, two alternative routes 4-10, one over crossover 1 reversed and the other over crossover 5 reversed. The button 8 affords a convenient means for selecting between these two, and accordingly the one over crossover 5 reversed is chosen as the preferred route to be set up in response to the successive operations of buttons 4P and 10P, and route 4-10 via crossover 1 reversed is chosen as the secondary route to be set up by first setting up route 4-8 and subsequently setting up route 8-10. It will be seen also that the track plan shows three different routes 4-12. The main line route with all switches normal is the only one set up in response to the operations of buttons 4 and 12, these operations having been already described. The "run around" route 4-12 over crossovers 5 and 7 reversed is purposely not provided for, while the secondary route 4-12 via crossovers 1 and 7 reversed may be set up by first setting up route 4-8 and subsequently setting up route 8-12, and it will be seen, therefore, that button 8 also affords a means of selection between these two available routes.

My apparatus is also arranged to provide "through routing" for routes 2-10 and 2-12 so that these routes may be set up by the successive operation of the buttons for the two ends without operating the intermediate button 8P, as I shall now describe.

Assuming that with the apparatus in the normal condition as shown, that buttons 2P and 10P are operated successively in that order. The operation of button 2P effects the energization of relays 2PS, ER and 8ES and relay 2PS prepares the circuit for relay 1ANR as already described for route 2-8; furthermore, relay 8ES prepares circuits for relays 7ANR, 7RR and 5ANR at its front contacts 125, 126 and 127, and button 10P when operated causes the successive energization of relays 7ANR and 5ANR, as already described for route 8-10. By reference to Fig. 1B it will be seen that when relay 8ES is picked up by closing contact 109 of relay 2PS, if button 8P is not operated to set up route 8-10 or 8-12, relay 8PS remains deenergized, and a circuit is completed from terminal B over back contacts 130 and 124 of relays 5ANR and 8PS, front con-

tact 136 of relay 8ES, relay 8XR to terminal C. Relay 8XR is thus energized in response to the energization of relay 2PS, and is released by relay 8ES when that relay is released in response to the opening of back contact 115 of relay 1ANR in setting up route 2-8. When the through route 2-10 or 2-12 is being set up, relay 5ANR becomes energized in response to the operation of the exit button as above described and releases relay 8XR by opening back contact 130. Relay 8XR is a slow-release relay, and when it is de-energized by relay 5ANR, a circuit is closed momentarily in Fig. 1C from terminal B over front contacts 137 and 138 of relays 5ANR and 8XR through relay 1ANR to terminal C at front contact 111 of relay 2PS, and relay 1ANR picks up to establish its stick circuit at contact 113 the same as if button 8P had been operated to close contact 29 momentarily. Relay 1ANR opens the pick-up circuit for relay 8ES of Fig. 1B at contact 115, but relay 8ES is now held energized over a stick circuit extending from terminal B at contact 131 of button 8P, front contact 139 of relay 5ANR, front contact 140 and winding of relays ES, contact 134 of relay 5TR to terminal C. It will be seen, therefore, that relays 2PS, 1ANR and 2HR for setting up route 2-8, and relays 8ES, 5ANR, 1ANR or 1RR and 8HR for setting up route 8-10 or 8-12 may be energized by the joint operation of buttons 2P and 10P or 2P and 12P only.

Considering now the route 10-2 governing train movements from right to left, it will be seen from Fig. 1C that when relay 10PS is energized and button 2P is operated, a circuit is completed from terminal B over front contact 27 of relay WR and contact 93 of button 2P through relay 1ANR to terminal C at front contact 141 of relay 10PS. Relay 1ANR upon becoming energized completes a stick circuit at contact 142, and at contact 143 completes a circuit from terminal B through relay 5ANR to terminal C at front contact 144 of relay 10PS. Relay 5ANR picks up and completes a circuit at its front contact 145 through relay 7ANR to terminal C at front contact 146 of relay 10PS, so that relays 1ANR, 5ANR and 7ANR become energized in response to the successive operation of buttons 10P and 2P to establish route 10-12.

For train movements from signal 10 to signal 4, the route 10-4 via 1 reversed is chosen as the preferred route by the provision of a circuit for picking up relay 1RR extending from terminal B at front contact 27 of relay WR over contacts 147 of button 4P, contact 148 of relay 10PS through relay 1RR to terminal C at front contact 141 of relay 10PS, over which relay 1RR becomes energized to establish its stick circuit at contact 149. Means are provided for setting up the secondary route 10-4 via 5 reversed, comprising a circuit for relay 1B-3NR extending from terminal B at contact 94 of button 4P which is completed in response to the operation of buttons 10P and 4P under the conditions first, that route 2-8 is set up, or second, that section 1T is occupied by a train and the crossover 1 is thereby locked normal with relay 1LR deenergized. Under the first condition, the circuit for relay 1B-3NR is completed over front contact 153 of relay 1ANR and contact 55 of relay 1NWP, and under the second condition, over back contact 154 of relay 1TR and contact 55 of relay 1NWP, thence to terminal C over front contact 151 of relay 10PS and back contact 152 of relay 5ANR. Relay 1B-3NR being energized under these conditions con-

ncts terminal B at front contact 97 of relay 1B-3NR to a circuit extending through relay 5RR to terminal C at front contact 155 of relay 10PS, thereby energizing relay 5RR to complete 5 a circuit from terminal B at its front contact 156 over back contacts 36, 145 and 125 through relay 7ANR to terminal C at front contact 146 of relay 10PS. It will be seen, therefore, that the route relays 1B-3NR, 5RR and 7ANR for route 10-4 10 via 5 reversed become energized in response to the successive operation of buttons 10P and 4P provided route 2-8 is set up or crossover 1 is normal and section 1T occupied.

The operations of setting up the main line 15 route 12-4 have already been described, but the track layout provides two other routes between the same route ends. As in the case of movements in the opposite direction, no provision is made for any train movements over route 12-4 via 7 20 and 5 reversed.

Normally when buttons 12P and 4P are operated, the circuit for relay 1RR is held open at contact 148 of relay 10PS and at contact 157 of the switch lever 1P, but the "run-around" route 25 12-4 via 7 and 1 reversed may be established by operating one of the switch levers to designate the desired alternative. With the circuits as shown, this selection is effected by moving lever 1P to its right-hand, or reverse, position. It will 30 be seen from Fig. 1D that this results in completing the reverse energizing circuit for relay 1WR at the right-hand contact 158 of lever 1P to effect the reversal of crossover switches 1A and 1B, while in Fig. 1C, when lever 1P is reversed, its contact 157 connects relay 1RR to contact 94 35 of button 4P in place of relay 1B-3NR. It will be seen that if buttons 4P and 12P are operated while lever 1P is reversed, relay 1RR will pick up over the circuit extending from terminal B at contact 27 of relay WR over contact 94 of button 4P through relay 1RR to terminal C over contact 85 of relay 12PS and back contact 150 of relay 5-7BNR and relay 1RR will complete a circuit from terminal B at back contact 159 of relay 4PS, front contact 160 of relay 1RR, through relay 5ANR to terminal C over front contact 86 of relay 12PS and back contact 161 of relay 5-7BNR. Relay 5ANR will therefore pick up and complete a circuit from terminal 40 B at its contact 162 through relay 7RR to terminal C at front contact 87 of relay 12PS to energize relay 7RR to complete the route set up for route 12-4 via 1 and 7 reversed.

Referring now to Fig. 1B, it has already been 45 pointed out how the buttons for the ends of the routes are rendered non-operative when a conflicting or opposing route is set up. Similar arrangements are provided for the apparatus associated with the intermediate button 8P. It will 50 be seen that when any route opposing or conflicting with route 8-10 is set up, the pick-up circuit for relay 8PS is held open at contact 163 or 133 of relay 5ANR or 5RR, so that contact 122 of button 8P is non-operative, and that the pick-up circuit for relay 8ES is held open at contact 115 or 164 of relay 1ANR or 5RR, contact 123 of relay 8PS being also open, while in Fig. 1C, the circuits over front contact 29 of button 8P are open 55 at contacts 118 and 98 of relays 2PS and 4PS.

In the foregoing I have explained but a few 60 of the many possible operations of the apparatus of my invention, but it is believed that since the remaining operations are carried out in a manner generally similar to those described that they will 65

be readily understood without further explanation.

Although I have herein shown and described only one form of apparatus embodying my invention, it is understood that various changes and modifications may be made therein within the scope of the appended claims without departing from the spirit and scope of my invention. 70

Having thus described my invention, what I claim is:

1. In an interlocking control system, a track layout including track switches operable to form different traffic routes, a route button for each route end in said layout, a directional relay for 15 each direction of traffic through said layout, an entrance relay for each route button, a pick-up circuit for each entrance relay closed in response to the momentary operation of the associated button but only if said directional relays are de- 20 energized, a stick circuit for each entrance relay including a normally closed contact controlled by the associated button, means effective when any entrance relay is initially energized for energizing the corresponding directional relay, route estab- 25 lishing means for each route effective when energized to govern the operation of the track switches as required to establish such route, means responsive to the momentary operation of the button for the exit end of a route having both 30 its entrance relay and the corresponding directional relay energized for energizing the route establishing means for such route, stick circuit means for maintaining such route establishing means energized until said entrance relay is released, and means controlled by such route establishing means when energized for preventing the energization of the route establishing means for any conflicting route and for releasing 35 said energized directional relay to render 40 the route buttons available for establishing other non-conflicting routes. 45

2. In an interlocking control system, a track layout including a plurality of track sections interconnected by track switches operable to form different traffic routes, a route button for each route end in said layout, a track relay for each track section, a directional relay for each direction of traffic through said layout, an entrance relay for each route button, route establishing 50 means for each route effective when energized to govern the operation of the track switches as required to establish such route, a pick-up circuit for each entrance relay closed in response to the operation of the associated route button 55 to identify the common entrance end of a plurality of diverging routes but only if said directional relays and the route establishing means for each of said diverging routes are deenergized, a stick circuit for each entrance relay controlled 60 by the associated button and by the track relay for the first section of said diverging routes, means controlled by each entrance relay for preparing circuits for the route establishing means for each of the associated diverging routes and 65 for energizing the directional relay for the corresponding traffic direction, means responsive to the operation of the route button for the exit end of any route having its entrance relay and the corresponding directional relay energized for en- 70 ergizing the route establishing means for such one route, stick circuit means for maintaining such route establishing means energized until said entrance relay is released, and means controlled by such route establishing means when 75

energized for preventing the energization of the route establishing means for any conflicting route and for releasing said energized directional relay to render the route buttons available for establishing other non-conflicting routes.

3. In an interlocking control system, a track layout including track switches operable to form different traffic routes, signals at the entrance ends of said routes for governing traffic movements in both directions, a route button for identifying each route end in said layout, two directional relays including one for each direction of traffic through said layout, route establishing means normally responsive to the successive operation of the two buttons identifying the opposite ends of a route for operating the track switches as required to establish such route and for clearing the signal at the end of such route corresponding to the button first operated, means responsive to the operation of said first operated button for energizing the directional relay for the traffic direction governed by such signal, means rendering any button operated when either directional relay is energized ineffective either to control the other directional relay or to control the route establishing means for any routes except those having a common exit end identified by such button, and means rendered effective upon the energization of a route establishing means for any conflicting route for releasing said energized directional relay to render the route buttons available for establishing other non-conflicting routes.

4. In combination, a track layout including track switches operable to form different traffic routes, a route button for each route end at each end of the track layout, two directional relays one for each end of the track layout, means effective when a route button is operated to energize the directional relay for the same end of the track layout provided said button is operated before any other route button is operated, and route establishing means rendered effective to establish the route connecting the corresponding route ends when such button is operated after the other directional relay has been energized in response to the operation of a button for a route end at the opposite end of the track layout.

5. In combination, a track layout including track switches operable to form different traffic routes, a signal for each track at each end of the layout for governing the movement of traffic over said routes, two directional relays one for each end of the track layout, a route button for each route end at each end of the track layout, means effective when a route button is operated to energize the directional relay for the same end of the track layout provided said button is operated before any button for a route end at the opposite end of the track layout is operated, route establishing means energized in response to the joint operation of the two buttons for the opposite ends of a route to operate the track switches as required to establish such route, means dependent upon which of the two directional relays is energized for selectively clearing one or the other of the two opposing signals for governing the movement of traffic over the established route, and means controlled by the energized route establishing means for releasing said energized directional relay.

6. In combination, a track layout including track switches operable to form different traffic routes, a control panel including a miniature

track diagram corresponding to said track layout, a route button for each route end at each end of said track layout located on said diagram in a corresponding location, a directional relay for each direction of traffic movements through said track layout, a direction indicator for each direction located on said control panel, means normally effective when a route button is operated to energize the directional relay for that direction which identifies the operated button as corresponding to the entrance end of a route, means effective as long as such directional relay is energized to illuminate the corresponding direction indicator, route establishing means responsive to the subsequent operation of a button for a route end at the opposite end of the track layout to establish the route extending between the route ends identified by the operated buttons, and means controlled by such route establishing means when operated for releasing said energized directional relay.

7. In combination, a track layout including track switches operable to form different traffic routes, a control panel including a route button for each route end at each end of said track layout, and a direction indicator for each direction of traffic movements through said track layout, means responsive to the successive momentary operations of the two buttons for the opposite ends of a route to establish that route through the track layout, means dependent only upon the relative order in which such two buttons are operated for determining the direction of traffic movements over that route when established, and means for illuminating the corresponding direction indicator to indicate such traffic direction following the operation of the first button and until the second button is operated.

8. In combination, a track layout including track switches operable to form different traffic routes, two directional relays, one for each end of the track layout, a route button for each route end at each end of the track layout, an entrance relay for each route end, a pick-up circuit for each entrance relay including a normally open contact controlled by the route button for the same route end and back contacts of both said directional relays, a stick circuit for each entrance relay for maintaining it energized when said contacts are open, means responsive to the energization of any entrance relay for energizing the directional relay for the same end of the track layout, route establishing means for each route effective when energized to operate the track switches as required for such route, means for initially energizing the route establishing means for a selected route in response to the operation of the route button for the exit end of such route when both the entrance relay for the opposite end of such route and the directional relay controlled thereby are energized, means for maintaining said route establishing means energized until such entrance relay is released, and means controlled by said route establishing means when energized for releasing said energized directional relay.

9. In combination, a track layout including track switches operable to form different traffic routes, two directional relays one for each end of the track layout, a route button for each route end at each end of the track layout, an entrance relay for each route end, route establishing means for each route effective when energized to operate the track switches as required for such route,

- a pick-up circuit for each entrance relay including a normally open contact controlled by the route button for the same route end, contacts closed only when no route having such route end 5 has been established and other contacts closed only when both said directional relays are de-energized, a stick circuit for each entrance relay for maintaining it energized when said contacts are open, means responsive to the energization of 10 any entrance relay for energizing the directional relay for the same end of the track layout, means for initially energizing the route establishing means for a selected route in response to the operation of the route button for the exit end 15 of such route when both the entrance relay for the opposite end of such route and the directional relay controlled thereby are energized, means for maintaining said route establishing means energized until such entrance relay is released, 20 and means responsive to the energization of said route establishing means for releasing said energized directional relay.
10. In combination, a track layout including track switches operable to form different traffic 25 routes with a signal for each track at each end of the layout, certain of said routes being located end-to-end to form a first and a second portion of a through route having an intermediate signal, a route button and an entrance relay for 30 each signal location, means normally effective when any route button is momentarily operated to energize the associated entrance relay, route establishing means for each route effective when energized to operate the track switches as required for such route, means responsive to the 35 operation of the route button for the exit end of a route having the entrance relay for its entrance end energized for energizing the route establishing means for such route, means for clearing the signal associated with the energized 40 entrance relay when such route becomes established, means responsive to the energization of the entrance relay for the first portion of said through route for energizing the entrance relay for said second portion, means effective when the 45 entrance relays for both portions of said through route are energized for energizing the route establishing means for both portions in response to the momentary operation of the button for the exit end of the second portion, means effective 50 if said intermediate button is operated to energize the route establishing means for the first portion only of said through route and to then release the entrance relay for said second portion, and means responsive to the release of said 55 intermediate button after such operation for conditioning the entrance relay for said second portion to be energized in response to a second operation of said button.
- 60 11. In an interlocking control system, a track layout including track switches operable to form different traffic routes, a normal and a reverse route relay for each track switch, a route circuit network including a plurality of normally open 65 circuits including one for each normal or reverse route relay each circuit corresponding to a route, or portion thereof, for which the track switch controlled by such route relay is required to occupy a corresponding normal or reverse position, a route button and an entrance relay for 70 each route end, means responsive to the operation of the button for one end of a selected route when no other route button has been operated for energizing the corresponding entrance relay, means controlled by each entrance

relay when energized for connecting one terminal of a source of current to one end of the circuits for all of the route relays for routes having a corresponding entrance end to prepare such circuits for energization, means responsive to 5 the momentary operation of the route button for the exit end of said selected route for connecting the other terminal of said source to the opposite end of the prepared circuit for the route relay for each switch of the selected route, means for subsequently maintaining such route relays energized until such entrance relay is released, and means controlled by each energized route relay for operating the corresponding track switch to normal or reverse as required for the selected 10 route.

12. In an interlocking control system, a track layout including track switches operable to form different traffic routes, a normal and a reverse route relay for each track switch, a route circuit 20 network including a plurality of normally open circuits including one for each normal or reverse route relay each circuit corresponding to a route, or portion thereof, for which the track switch controlled by such route relay is required to occupy a corresponding normal or reverse position, a route button and an entrance relay for each route end, means responsive to the operation of the button for one end of a selected route when no other route button has been operated for energizing the corresponding entrance relay, means controlled by each entrance relay when energized for connecting one terminal of a source of current to one end of the circuits for all of the route relays for routes having a corresponding 30 entrance end to prepare such circuits for energization, means responsive to the momentary operation of the route button for the exit end of said selected route for connecting the other terminal of said source to the opposite end of the prepared circuit for the route relay for the last track switch in said selected route, a stick circuit for maintaining said last named route relay energized until such entrance relay is released, means responsive to the energization of each route relay 35 for a switch in said selected route for energizing the route relay for the next preceding switch in such route, and means controlled by each energized route relay for operating the corresponding track switch to normal or reverse as required 40 for the selected route.

13. In combination, a track layout including track switches operable to form different traffic routes, a route button for each route end at each end of the track layout, two directional relays 55 one for each end of the track layout, means effective when a route button is operated to energize the directional relay for the same end of the track layout provided said button is operated before any other route button is operated, a normal and a reverse route relay for each track switch, each effective when energized to operate the track switch to corresponding normal or reverse position, and means for energizing selected ones of said route relays as required to 60 establish the route connecting the corresponding route ends when such button is operated after the other directional relay has been energized in response to the operation of a button for a route end at the opposite end of the track layout.

14. In combination, a track layout including track switches operable to form different traffic routes, a route button for each route end at each end of said track layout, two directional relays one for each direction of traffic movements 70

through said track layout, means responsive to the successive momentary operation of the two buttons for the opposite ends of a route to establish that route through the track layout and to energize one directional relay or the other, dependent upon which of the two buttons is

operated first, and means controlled by the energized directional relay for determining the direction of traffic movements over that route when established.

CHARLES H. LAY.
